CURRENT TAP CHANGING SYSTEM

Bernhard Jansen, Regensburg, Germany

Application March 7, 1951, Serial No. 214,279

3 Claims. (Cl. 323—43.5)

1

The present invention relates to transfer switches for operation under load, and more particularly to switches of this character which are suitable for use in changing transformer taps under load.

An object of the invention is to provide a transfer switch of this character in which the load current is divided among three separate pairs of contacts, so arranged that the load current will be equally distributed to minimize arcing and the accompanying burning of the contacts.

A feature of the invention resides in the provision of inductively coupled current dividing circuit elements which act to equalize the distribution of the load current, particularly during transient conditions when contact arcing is taking place. The inductive coupling is so arranged that, during initial contact opening under load, if the arc at one of the contacts should become extinguished, the accompanying increase in current flow through the other contacts will induce a voltage sufficient to restrike the arc and redistribute the arcing substantially equally among the contacts. This technique has previously been applied to mercury vapor rectifiers for a two-way division of the load. The present invention, however, provides for a three-way load division.

The present invention permits the operation of three pairs of equally rated contacts to obtain a current rating for the group of three times the individual rating of each contact pair and avoids the necessity for precise mechanical adjustments to obtain equal current distribution and distribution of arcing among the three contact pairs.

Other objects and advantages will become apparent upon reading the following specification together with the accompanying drawing forming a part hereof.

Referring to the drawing:

Figure 1 is a schematic circuit diagram illustrating an embodiment of the invention as applied to a transformer tap preselector and changeover switch for changing transformer taps under load, the inductively coupled load equalizing circuit elements being connected between the tap preselector and the changeover switch.

Figure 2 is similar to Fig. 1, except that the changeover switch is provided with additional contacts which normally short circuit the inductively coupled circuit elements and introduce them in the circuit only momentarily during the short interval of operation of the changeover switch.

Figure 3 is similar to Fig. 1, except that the inductive circuit elements are associated with

the line conductor leading to the changeover switch.

Fig. 1 shows a transformer tap changing regulating switch with three-way current division between the tap preselector and the load changeover switch by permanently connected current equalizers with separate magnetic cores (left) and with a common core (right). The tap preselector represented in the lower part of the drawing by the 6 tap contact surfaces Wa_1 to Wa_3 and Wb_1 to Wb_3 and by the 6 movable contacts a_1 to a_3 and b_1 to b_3 , which are connected to the two transformer taps A and B. This three-way division is continued after passing through the current equalizing windings and in the load changeover switch Ha_1 to Ha_3 and Hb_1 to Hb_3 through the three switch arms L_1 to L_3 , the three switch arms L_1 to L_3 being shown connected to a common line conductor A.

Equalization of the current division is effected, as shown on the left side, by the inductively coupled windings a_{11} and a_{12} which oppose each other, having a common magnet core Sta_1 . Similarly the inductively coupled windings a_{21} and a_{22} are provided with a common core Sta_2 and the windings a_{31} and a_{32} are coupled by a common magnetic core Sta_3 , each of the three pairs of inductively coupled windings being provided with an individual magnetic core. The arrows shown in the drawing indicate the direction of the magnetic flux generated by each individual winding. If the individual winding currents are equal, these magnetic fluxes neutralize each other.

Referring to the modified arrangement on the right hand side of Fig. 1, the three pairs of inductively coupled windings are shown provided with a common magnetic core Stb . The arrows indicate the direction of flux assuming that the arc drawn at changeover switch contacts Hb_1 and Hb_3 by interruption of current flowing through tap preselector switch contact b_1 is prematurely extinguished during movement of the load changeover switch arms L_1 to L_3 toward the left from the position shown in dotted lines toward the position shown in solid lines, as indicated by the arrows. The current in each of

the other two branches b_2 and b_3 suddenly increases from $\frac{1}{3}$ of the total current to a value of $\frac{2}{3}$ of the total current. The flux produced in the middle core leg is balanced out. The magnetization in the two outer legs is such as to cause flux to flow around the core structure as indicated by the arrows. The relative polarities of the windings are so arranged that the load carrying windings b_{12} and b_{31} induce cumulative voltages

55

in the series connected windings b_{32} and b_{11} , current flow through windings B_{32} and b_{11} having been interrupted by the assumed premature extinguishing of the arc at changeover switch arm L_1 . The direction of these induced voltages is such as to raise the voltage at stationary contacts Hb_1 and hb_1 , thereby tending to restrike the prematurely extinguished arc and equalize the arcing at the three switch arms L_1 to L_3 of the changeover switch. By suitably dimensioning the two electromagnetic structures each comprising three pairs of inductively coupled coils, the magnitude of the induced voltage accompanying a premature decrease in current in any of the three circuit branches may be made sufficient to restore the prematurely decreasing current to its proper value, restriking an arc, if necessary.

Fig. 2 shows a regulating switch with three-way current division between the tap preselector and the load changeover switch, the inductively coupled circuit elements being effective only momentarily during the relatively short interval of switching operation of the load changeover switch. The current equalizing circuit elements are normally short-circuited through the stationary main contacts and stationary switching Ha_1 — Da_1 , Ha_2 — Da_2 and Ha_3 — Da_3 which are bridged by the switch arms L_1 , L_2 and L_3 , respectively, in one of the two normal positions of the changeover switch as shown in Fig. 2 of the drawing. The stationary contacts Hb_1 — Db_1 , Hb_2 — Db_2 and Hb_3 — Db_3 are similarly bridged by the switch arms L_1 , L_2 and L_3 , respectively, when the changeover switch is operated to its other normal position by moving the switch arms L_1 to L_3 to the right, or in a clockwise direction as viewed in Fig. 2, thereby short circuiting the inductively coupled circuit elements shown on the right hand side of Fig. 2 which are coupled by a common unitary magnetic core structure.

The divided current loads from the preselected transformer tap leads A and B flow through either of the two groups of main stationary contacts Da_1 to Da_3 or Db_1 to Db_3 , respectively in each of the two positions of the changeover switch. As in Fig. 1, the currents from the three switch arms L_1 to L_3 of the changeover switch are combined in the common line conductor A_1 . Assuming the changeover switch to be in the position shown in Fig. 2, as the switch arms L_1 to L_3 move toward the right, the circuit through the main stationary contacts Da_1 to Da_3 is broken and the three load currents flow through the main switching contacts Ha_1 to Ha_3 , passing through the left hand group of inductively coupled current equalizing circuit elements. The main stationary contacts Da_1 to Da_3 are not designed to withstand arcing, and the potential drop across the current equalizing circuit elements must accordingly be limited to a value sufficiently small to prevent appreciable arcing. As the switch arms L_1 to L_3 proceed further toward the right, the circuit is broken and arcing occurs at the main switching contacts Ha_1 to Ha_3 , the three currents being equalized by the left hand group of inductively coupled circuit elements as this arcing occurs. The final current interruption takes place with the current equalizers in the circuit as the three switch arms L_1 to L_3 disengage the auxiliary switching contacts ha_1 to ha_3 which are connected to the respective

main switching contacts Ha_1 to Ha_3 through non-inductive resistors. A similar switching sequence takes place as the switch arms L_1 to L_3 are moved back from their right hand position to their original starting position shown in Fig. 2.

Fig. 3 shows a regulating switch with three-way equalized current division, in which the inductively coupled current equalizing circuit elements are connected between the main line conductor A_1 and the three switch arms L_1 to L_3 of the changeover switch. Using this arrangement, only one set of current equalizing circuit elements is required, however, the three switch arms L_1 to L_3 must be insulated from each other.

In the arrangements of Fig. 1 and Fig. 3, the current equalizing circuit elements must be designed for continuous duty and must be capable of withstanding the usual current surges on the line. In the arrangement of Fig. 2, the current equalizing circuit elements may be designed for momentary duty and are not required to withstand surge currents, except if a surge should occur during the instant of changeover switch operation.

In the arrangements of Figs. 1 and 3, the current equalizing circuit elements are continuously effective for the load currents so that the load currents flowing through the three switch arms L_1 to L_3 will be equalized and the heating of the switch contacts will accordingly be equalized.

I claim:

1. Current equalizing means of the class described, comprising: two conductors to be connected and disconnected from each other for closing and opening a circuit; three pairs of co-operating switch contacts of equal ratings, one contact of each of said contact pairs being connected to one of said conductors; three pairs of inductively coupled circuit elements, each circuit element having two terminals, one terminal of one circuit element of each pair being connected to the other contact of each of said contact pairs and one terminal of the other circuit element of each pair being connected to the other of said two conductors, the remaining terminal of each of said circuit elements being connected to the remaining terminal of one of the circuit elements of another pair to complete a circuit from one of said other contacts to said other conductor, the respective polarities of the inductive coupling between each pair of circuit elements being such that a reduction in current flow through one of said contact pairs tending to increase current flow through the other two contact pairs induces a cumulative voltage in the two circuit elements connected between said contact pair in which said current reduction takes place and said other conductor tending to increase said reduced current flow and prevent said current reduction, whereby equal current distribution in said three pairs of cooperating contacts is maintained.

2. Current equalizing means according to claim 1, in which said inductively coupled circuit elements are coupled through a common magnetic core structure.

3. Current equalizing means according to claim 1, in which the inductively coupled circuit elements of each pair are coupled through an individual magnetic core structure.
